(57) CLAIM

The ornamental design for a support element for an undergarment, as shown and described.

DESCRIPTION

FIG. 1 is a top front perspective view of a support element for an undergarment, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a top rear perspective view thereof.

The evenly-sized dash-dash broken lines showing an undergarment depicts environmental subject matter that forms no part of the claimed design.

The unevenly-sized dash-dot-dash broken lines depicts the boundary of the claim that forms no part of the claimed design.

1 Claim, 5 Drawing Sheets
